UNITED STATES PATENT OFFICE

REGINALD STUART GODDARD, OF BATTERSEA, ENGLAND

DESIGN FOR A PLAYING TABLE

Application filed May 6, 1930. Serial No. 35,505. Term of patent 7 years.

To all whom it may concern:

Be it known that I, REGINALD STUART GODDARD, a subject of the King of Great Britain and Ireland, and a resident of Battersea, county of London, England, have invented a new, original, and ornamental Design for Playing Table, of which the following is a specification, reference being had to the accompanying drawing, forming part thereof.

Figure 1 is a perspective view of the playing table showing my new design.

Figure 2 is a transverse cross sectional view of the playing table shown in Figure 1.

I claim:

The ornamental design for a playing table, as shown.

In testimony whereof I have affixed my signature hereto this 16th day of April, 1930.

REGINALD STUART GODDARD.
